UNITED STATES PATENT OFFICE

WILLIAM H. DURANT, OF READING, MASSACHUSETTS

DOORSTOP

Application filed November 4, 1931. Serial No. 572,955.

This invention relates to a door stop adapted to bear on opposite sides of an open door and on a floor under the door, to confine the door against accidental movement from an opened position.

The invention is embodied in improvements rendering a stop of this character more desirable in certain respects than others heretofore provided.

10 Of the accompanying drawing forming a part of this specification Figures 1 and 2 show in perspective a door stop embodying the invention and a portion of a door, the door shown by Figure 1 being called a high hung door, while that shown by Figure 2 is called a low hung door.

Figure 3 is a bottom view of one of the feet shown by Figures 1 and 2.

Figure 4 is a perspective view showing the 20 foot provided with studs and a loop.

Figure 5 shows in section one of the blocks shown by Figures 1 and 2 and a foot and loop constructed as shown by Figure 4.

Figure 6 is a side view showing one of the 25 blocks provided with a clamping member, the neck connecting the blocks with another block being shown in section.

Figure 7 shows one of the blocks in section on line 7—7 of Figure 6, the other block being 30 shown in elevation.

Figure 8 shows in perspective the clamping member shown by Figures 6 and 7.

The same reference characters indicate the 35 same parts in all of the figures.

My improved door stop is adapted for use with either a high hung door whose lower end may be an inch or more above the floor, or a low hung door whose lower end may be approximately half an inch or less above the floor.

The stop comprises a pair of blocks 12 having flat oblong faces arranged to bear on a floor, opposed inner sides arranged to face 45 opposite sides of a door, and a neck 14 rigidly attached to the blocks and spacing them apart with their inner sides substantially parallel with each other. The blocks and neck may be of cast metal cast in one piece, 50 or the blocks may be cast upon the end por-

tions of a separately formed neck or otherwise united thereto.

The neck 14 is formed to enter the space between the lower end of a high hung door D (Figure 1) and a floor supporting the stop, so that the stop may be located on the floor at any desired distance inward from the swinging edge of the door.

The neck is located at one side of the longitudinal centers of the blocks so that it constitutes one end of a door receiving recess between the major portions of the blocks, and is adapted to abut the swinging edge of a low hung door D' (Fig. 2) in said recess, so that although the neck cannot be located in the space under the door D', the major portions of the block 12 may be located at opposite sides of said door in position to oppose accidental swinging thereof. The neck is movable inwardly under a high hung door to locate all portions of the blocks beside the door as indicated by Figure 1, so that the blocks do not project from the swinging edge of the door, and do not constitute an obstruction at said swinging edge.

To prevent rattling contact between the sides of the door and the inner sides of the blocks 12 I provide said inner sides with anti-rattling buffers arranged to contact noiselessly with opposite sides of a door portion between the blocks. Each buffer may be one side of a loop 17 of elastic or other suitable material extending vertically across the mid length portion of the block sides, the loops being confined against edgewise displacement by the blocks preferably by grooves 18 formed in the upper edges of the blocks. The buffers are formed to project outwardly from the sides of the blocks and prevent contact of any portion of the blocks with the door.

To cause a frictional engagement between the blocks and the floor I provide feet 19 of rubber or other suitable frictional material united to the ends of the loops and bearing on and covering the bottoms of the blocks, said feet being adapted to frictionally engage a floor and oppose movement of the blocks thereon. The bottom surfaces of said feet are provided with oblique grooves 19a.

forming oblique corrugations (Fig. 3) having flat faces bearing on a floor. The oblique edges of said faces are longer than they would be if the corrugations were not oblique, and therefore have a more effective engagement with the floor.

Each foot and loop may be molded in one piece, or the ends of the loops may be united by vulcanization to opposite edges of the 10 feet, the loops upstanding from the feet, and being normally contracted so that they may be stretched and allowed to spring into the grooves 18. The loops confine the feet against the bottoms of the blocks 12.

15 To additionally secure the feet 19 to the blocks I provide the bottoms of the blocks with sockets 20 receiving stud portions 21 of the feet, so that endwise and edgewise displacement of the feet are prevented.

20 To enable the stop to engage both sides of doors of different thickness I may provide one of the blocks 12 with a clamping member movable relative to the block to bear on one side of a door and clamp the opposite side thereof against the other block.

25 Said member preferably includes a bell crank lever including arms 24 and 28 and fulcrumed at 25 in a recess 26 in one block. The arm 24 has a face 27 which is movable by an operator through the arm 28, to exert pressure on one side of a door as indicated by dotted lines in Figure 7. The face 27 is preferably of rubber adapted to frictionally engage the door, and has a tongue 29 entering a groove 30 in the lever.

30 I prefer to provide the loop 17 with vertically arranged beveled edge faces 31 on one or both of its sides, thus preventing the formation of shoulders liable to catch on or interfere with a door when the stop is being moved into engagement therewith. Although the faces 31 are required only on the inner sides of the loops I prefer to provide them on both sides, because by so doing 45 I am enabled to apply the feet and loops to the blocks without taking care in locating beveled faces on the inner sides of the blocks.

I claim:

1. A door stop comprising a pair of blocks 50 formed to rest on a floor, and having opposed inner sides arranged to face opposite sides of a door, and a neck rigidly attached to the blocks and spacing them apart with their inner sides substantially parallel with each 55 other, the neck being formed to enter the space between the lower end of a high hung door and a floor, and permit the location of the blocks at various distances from the swinging edge of the door, the neck being located at one side of the longitudinal centers 60 of the blocks so that it constitutes an end of a door receiving recess between the major portions of the blocks, and is adapted to about the swinging edge of a low hung door in said recess, said blocks being provided with 65 anti-rattling buffers extending vertically across the mid length portions of their sides and projecting outwardly therefrom to prevent contact of any portions of the blocks with the door.

70 2. A door stop comprising a pair of blocks formed to rest on a floor, and having opposed inner sides arranged to face opposite sides of a door, and a neck rigidly attached to the blocks and spacing them apart with their inner sides substantially parallel with each other, the neck being formed to enter the space between the lower end of a high hung door and a floor, and permit the location of the blocks at various distances from the swinging edge of the door, the neck being located at one side of the longitudinal centers of the blocks so that it constitutes an end of a door receiving recess between the major portions of the blocks, and is adapted to about the swinging edge of a low hung door in said recess, said blocks being provided with 75 anti-rattling buffers arranged to contact with the opposite sides of a door portion between the blocks, and with oblong feet of frictional material entirely covering their bottoms and adapted to frictionally engage a floor.

80 3. A door stop comprising a pair of blocks formed to rest on a floor, and having opposed inner sides arranged to face opposite sides of a door, and a neck rigidly attached to the blocks and spacing them apart with their inner sides substantially parallel with each other, the neck being formed to enter the space between the lower end of a high hung door and a floor, and permit the location of the blocks at various distances from the swinging edge of the door, the neck being located at one side of the longitudinal centers of the blocks so that it constitutes an end of a door receiving recess between the major portions of the blocks, and is adapted to about the swinging edge of a low hung door in said recess, said blocks being provided with 85 anti-rattling buffers arranged to contact with the opposite sides of a door portion between the blocks, and with oblong feet of frictional material entirely covering their bottoms and adapted to frictionally engage a floor.

90 4. A door stop comprising a pair of blocks formed to rest on a floor, and having opposed inner sides arranged to face opposite sides of a door, and a neck rigidly attached to the blocks and spacing them apart with their inner sides substantially parallel with each other, the neck being formed to enter the space between the lower end of a high hung door and a floor, and permit the location of the blocks at various distances from the swinging edge of the door, the neck being located at one side of the longitudinal centers of the blocks so that it constitutes an end of a door receiving recess between the major portions of the blocks, and is adapted to about the swinging edge of a low hung door in said recess, said blocks being provided with 95 anti-rattling buffers arranged to contact with the opposite sides of a door portion between the blocks, and with oblong feet of frictional material adapted to frictionally engage a floor, said feet having obliquely corrugated bottom faces.

100 5. A door stop comprising a pair of blocks formed to rest on a floor, and having opposed inner sides arranged to face opposite sides of a door, and a neck rigidly attached to the blocks and spacing them apart with their inner sides substantially parallel with each other, the neck being formed to enter the space between the lower end of a high hung door and a floor, and permit the location of the blocks at various distances from the swinging edge of the door, the neck being located at one side of the longitudinal centers of the blocks so that it constitutes an end of a door receiving recess between the major portions of the blocks, and is adapted to about 105 the swinging edge of a low hung door in said recess, said blocks being provided with anti-rattling buffers arranged to contact with the opposite sides of a door portion between the blocks, and with oblong feet of frictional material adapted to frictionally engage a floor, said feet having obliquely corrugated bottom faces.

110 6. A door stop comprising a pair of blocks formed to rest on a floor, and having opposed inner sides arranged to face opposite sides of a door, and a neck rigidly attached to the blocks and spacing them apart with their inner sides substantially parallel with each other, the neck being formed to enter the space between the lower end of a high hung door and a floor, and permit the location of the blocks at various distances from the swinging edge of the door, the neck being located at one side of the longitudinal centers of the blocks so that it constitutes an end of a door receiving recess between the major portions of the blocks, and is adapted to about 115 the swinging edge of a low hung door in said recess, said blocks being provided with anti-rattling buffers arranged to contact with the opposite sides of a door portion between the blocks, and with oblong feet of frictional material adapted to frictionally engage a floor, said feet having obliquely corrugated bottom faces.

120 7. A door stop comprising a pair of blocks formed to rest on a floor, and having opposed inner sides arranged to face opposite sides of a door, and a neck rigidly attached to the blocks and spacing them apart with their inner sides substantially parallel with each other, the neck being formed to enter the space between the lower end of a high hung door and a floor, and permit the location of the blocks at various distances from the swinging edge of the door, the neck being located at one side of the longitudinal centers of the blocks so that it constitutes an end of a door receiving recess between the major portions of the blocks, and is adapted to about 125 the swinging edge of a low hung door in said recess, said blocks being provided with anti-rattling buffers arranged to contact with the opposite sides of a door portion between the blocks, and with oblong feet of frictional material adapted to frictionally engage a floor, said feet having obliquely corrugated bottom faces.

the swinging edge of a low hung door in said recess, said blocks being provided with anti-rattling buffers arranged to contact with the opposite sides of a door portion between the blocks, and with oblong feet of frictional material adapted to frictionally engage a floor, the said buffers being the inner sides of elastic loops joined to and upstanding from the feet and confined in grooves in the blocks, said loops confining the feet against the bottoms of the blocks.

5. A door stop comprising a pair of blocks formed to rest on a floor, and having opposed inner sides arranged to face opposite sides of a door, and a neck rigidly attached to the blocks and spacing them apart with their inner sides substantially parallel with each other, the neck being formed to enter the space between the lower end of a high hung door and a floor, and permit the location of the blocks at various distances from the swinging edge of the door, the neck being located at one side of the longitudinal centers of the blocks so that it constitutes an end of a door receiving recess between the major portions of the blocks, and is adapted to abut the swinging edge of a low hung door in said recess, said blocks being provided with anti-rattling buffers arranged to contact with the opposite sides of a door portion between the blocks, and with oblong feet of frictional material adapted to frictionally engage a floor, the said buffers being the inner sides of elastic loops joined to and upstanding from the feet and confined in grooves formed in the blocks, said loops confining the feet against the bottoms of the blocks, the loops being provided with vertically arranged beveled edge faces formed to prevent interference with the door when the stop is being moved into engagement therewith.

6. A door stop comprising a pair of blocks formed to rest on a floor, and having opposed inner sides arranged to face opposite sides of a door, and a neck rigidly attached to the blocks and spacing them apart with their inner sides substantially parallel with each other, the neck being formed to enter the space between the lower end of a high hung door and a floor, and permit the location of the blocks at various distances from the swinging edge of the door, the neck being located at one side of the longitudinal centers of the blocks so that it constitutes an end of a door receiving recess between the major portions of the blocks, and is adapted to abut the swinging edge of a low hung door in said recess, said stop comprising also a clamping member engaged with one of the blocks and movable relative thereto to bear on one side of a door and clamp the opposite side against the other block.

7. A door stop comprising a pair of blocks formed to rest on a floor, and having opposed inner sides arranged to face opposite sides

of a door, and a neck rigidly attached to the blocks and spacing them apart with their inner sides substantially parallel with each other, the neck being formed to enter the space between the lower end of a high hung door and a floor, and permit the location of the blocks at various distances from the swinging edge of the door, the neck being located at one side of the longitudinal centers of the blocks so that it constitutes an end of a door receiving recess between the major portions of the blocks, and is adapted to abut the swinging edge of a low hung door in said recess, said stop comprising also a clamping member engaged with one of the blocks and movable relative thereto to bear on one side of a door and clamp the opposite side against the other block, said member including a bell crank lever fulcrumed in a recess in one of the blocks, one arm of said lever having a frictional face which is movable by the lever to clamp one side of a door against the other block, the other lever arm projecting outward from the recessed block, and movable by an operator to force said jaw against a door portion between the blocks.

In testimony whereof I have affixed my signature.

WILLIAM H. DURANT.
